BICYCLE RACK

Ronald L. Ewers, Litchfield, Mich., assignor to Game Time, Inc., Litchfield, Mich.

Filed Dec. 12, 1973, Ser. No. 423,994

Term of patent 14 years

Int. Cl. D8—99

U.S. Cl. D12—115

—FIG. 1

—FIG. 3

FIG. 1 is a perspective view of a bicycle rack showing my new design.

FIG. 2 is a side elevational view thereof, and FIG. 3 is a top plan view thereof.

I claim:

The ornamental design for a bicycle rack, substantially as shown.
